VEHICLE-WHEEL WRENCH AND EXTENSION-HANDLE ASSEMBLY

Howard Hinds Lane, Dearborn, Mich., assignor
of fifty per cent to Lloyd Lawson, Dearborn,
Mich.

Application February 17, 1949, Serial No. 76,883

10 Claims. (Cl. 81—177)

1

This invention relates to a wrench and more particularly to a wrench useful for securing in place or removing the nuts or lag screws which secure a vehicle wheel, such as an automotive truck or trailer wheel, to the hub.

A truck or trailer wheel, in most cases, is considerably larger than a passenger vehicle wheel and the nuts or lag screws which secure such a wheel to the hub tighten down in operation and frequently rust in position. Because of this, considerable leverage or torque is required to loosen such a nut or lag screw.

It is an object of this invention to produce a wrench assembly which gives the operator considerable leverage when used to secure the nuts or lag screws in place or to remove them, and which can be easily disassembled and stored in a minimum of room.

My wrench is of simple and rugged structure and economical to manufacture.

In the drawings:

Fig. 1 is an assembly plan view of my wrench with the wrench in position for turning large diameter nuts or lag screws.

Fig. 2 is an assembly view of my wrench with the wrench in position for turning small diameter nuts or lag screws.

Fig. 3 is a right end view of either Figs. 1 or 2.

Fig. 4 is an elevational view of the three members which compose my wrench assembly.

Fig. 5 is a section along the line 5—5 of Fig. 3.

Fig. 6 is a section similar to Fig. 5 but showing the wrench shifted through the handle to a position for turning large nuts, such position being shown in Fig. 1.

Fig. 7 is a section taken along the line 7—7 of Fig. 2.

Referring to the drawings (Fig. 4) it will be seen that my wrench assembly comprises three main elements; namely, wrench 1, handle 2 and key 3. Wrench 1 takes the form of a double ended socket wrench comprising a cylindrical or rod-like body 4 having integral sockets 5 and 6 at its opposite ends. Sockets 5 and 6 are shown as conventional hexagonal sockets but can be made any shape to conform to the head of the lag screw, bolt, or nut which is to be operated thereby. Socket 6 has a large diameter than socket 5.

The wrench body 4 is provided preferably adjacent each socketed end with a pair of transverse openings 7 and 8 respectively. Openings 7 and 8, for descriptive purposes, are shown as cylindrical openings but can be elliptical or polygonal in cross-section if desired.

2

Handle 2 comprises an adapter body 9 and a handle 10. By way of illustration, adapter body 9 and handle 10 are shown as two separate elements but can be made integral. As shown, adapter body 9 is provided with an axial recess 11 in which one end of the tubular handle 10 is seated and the two elements are joined together by welding as at 12. Handle 2 is provided with an axial opening 13 which is traversed by stop pin 14. Axial opening 13 intersects a transverse opening 15 which, for purposes of description, is shown as cylindrical to conform to the cylindrical external contour of sockets 5 and 6. Obviously the contour of opening 15 will correspond with, and depend upon, the external contour of sockets 5 and 6. One end of opening 15 is tapered or conical as at 16 to correspond with the conical surface 17 of the larger socket portion 6.

Key member 3 is in the form of a cylindrical rod, an outer end 18 of which can be used as a lever handle.

When not in use the parts will be disassembled as shown in Fig. 4, and since each of the three members comprises in essence a cylindrical rod, it is evident that they can be stored in a minimum of space.

To assemble the wrench for use, assuming that one desires to use the large socket 6, then the small socket 5 end of the wrench 1 is inserted in transverse opening 15 and the axial opening 13 of the handle 9, 10 is aligned with opening 7 in socket portion 5. With the openings thus aligned, key or rod 3 is slid into the opening 13 through its entrance end 20 and passed through opening 7 in order to key handle 9, 10 and wrench 1 together. An inner end 21 of key 3 abuts stop 14 so that preferably, but not necessarily, a portion 18 of key 3 extends beyond entrance 20 in adapter body 9 and thus can be used as one of the lever handles.

If it is desired to use the small wrench socket 5, wrench 1 is slid through opening 15 until the conical portion 17 of socket 6 engages the taper 16 in opening 15, then transverse opening 8 in socket 6 is aligned with axial opening 13, and finally key 3 is passed through openings 13 and 8 in order to key the wrench to the handle 9, 10 in the same manner as previously described.

To disassemble the wrench, key 3 is removed from opening 7 or 8, whichever the case may be, and opening 13, thus permitting the wrench 1 to be withdrawn from opening 15 and disassembled from the handle 9, 10.

In actual practice I have found that by making handle 9, 10 about thirty inches long that my

wrench can be used to remove the lag screws and nuts from the largest truck and trailer wheels now in commercial use with considerable ease and in some instances where the nut or lag screw is rusted in place, the operator can stand on the wrench handle 10 or even jump on the same so that the torque applied by the socket wrench 1 is sufficient to remove even the most difficult nuts and lag screws encountered in removing the heaviest of the truck and trailer wheels.

I claim:

1. The assembly comprising in combination a wrench, a removable handle having intersecting axial and transverse openings therein, said wrench having an opening therethrough and being insertable in the transverse opening in said handle so that the opening in the wrench is aligned with the axial opening in said handle, and a key member removably inserted in said axial opening in the handle and passed through the opening in said wrench in order to key the handle and wrench together.

2. The assembly claimed in claim 1 wherein the axial opening in the handle extends inwardly from one end of the handle.

3. The assembly claimed in claim 2 wherein the transverse opening in the handle extends completely through the handle.

4. The assembly claimed in claim 3 wherein the wrench is provided with an enlarged end in the form of a socket having a diameter larger than the diameter of the transverse opening in the handle, and wherein the opening through the wrench is positioned adjacent said socket; whereby, when the wrench is inserted in said transverse opening so that the opening in the wrench aligns with the axial openings in the handle, the enlarged socketed head with abut the handle.

5. The assembly claimed in claim 4 wherein the wrench is in the form of a cylindrical rod with a socket at each end, one socketed end of the wrench having a diameter greater than, and the other socketed end of the wrench having a diameter less than, the diameter of the transverse opening in the handle; whereby, when the small diameter end of the wrench is passed through the transverse opening until the large diameter end of the wrench abuts the handle, the opening in the wrench can be aligned with the axial opening in the handle.

6. The assembly comprising in combination a wrench, a removable handle having intersecting axial and transverse openings therein, said

wrench having an opening therethrough and being insertable in the transverse opening in said handle so that the opening in the wrench is aligned with the axial opening in said handle, 5 and a key member removably inserted in said axial opening in the handle and passed through the opening in said wrench in order to key the handle and wrench together, said axial opening extending inwardly from one end of said handle 10 to provide an entrance for said key, a stop in said axial opening against which the inserted end of said key abuts when the wrench, handle and key are assembled together, said transverse opening in the handle being positioned between the entrance end of said axial opening and said stop.

7. The assembly claimed in claim 6 wherein the axes of said axial and transverse openings are substantially perpendicular and wherein the axis of the opening through said wrench is substantially perpendicular to the longitudinal axis of the wrench.

8. The assembly claimed in claim 7 wherein the key in assembled position projects beyond the end of said handle so that the outer end of the key 25 serves as a lever handle.

9. The assembly claimed in claim 7 wherein the wrench is in the form of a cylindrical rod having a small diameter socket at one end and a large diameter socket at the other end, and wherein 30 the wrench has two openings therethrough, one adjacent each socketed end, said openings selectively receiving said removable key member.

10. The assembly claimed in claim 9 wherein the large socket end of the wrench has a larger 35 diameter than the diameter of said transverse opening and the small diameter socket end of said wrench has a diameter less than the diameter of the transverse opening in the handle, the large diameter socket end of said wrench abutting the handle in one end of the transverse opening in order to assist in aligning the opening in the wrench with the axial opening in the handle.
